UNITED STATES PATENT OFFICE.

HARMON P. ELLIOTT, OF NEWTON, MASSACHUSETTS.

INK-ROLL FOR PRINTING-PRESSES.

Specification of Letters Patent. Patented Aug. 20, 1912.

1,036,200.

Application filed December 5, 1910. Serial No. 595,540.

To all whom it may concern:

Be it known that I, HARMON P. ELLIOTT, residing at Newton, in the county of Middlesex and State of Massachusetts, have invented an Improvement in Ink-Rolls for Printing-PresSES, of which the following is a specification.

This invention relates to ink-rolls for printing presses, and similar devices.

10 Prior to my invention an ink-roll has been constructed consisting of a hollow cylinder having small perforations in its cylindrical wall, and containing a radially disposed frame-bar with a beveled edge, arranged to force the ink through the perforations as one of said parts is moved with respect to the other; and this invention has for its object to provide said roll with means, whereby ink may be delivered to it without 15 wholly or partially disassembling it, and, if desired, without removing it from its bearings.

Figure 1 is a plan view of an ink-roll having means embodying this invention for delivering ink thereto. Fig. 2 is a longitudinal section of the ink-roll shown in Fig. 1, taken on the dotted line 2—2. Fig. 3 is a sectional detail of a portion of the ink-well, showing a tube of ink connected thereto.

a represents a hollow cylinder having a plurality of small perforations a' in its wall, and having at one end a circular closing plate b provided on its inner face with a center-hole b', and on its outer face with a 35 stub shaft b², and having at its opposite end a circular plate d with a large circular hole through it which receives a circular plate d' formed with a center hole through it and with a shoulder d² on its outer face around 40 said center-hole. The frame-bar contained in said hollow cylinder is shaped like unto a double crank, and comprises a bar e extended lengthwise the cylinder, having arms e' at its opposite ends, each arm having an 45 outwardly extended gudgeon, one of which as e², enters the center-hole in the closing plate b, and the other as e³, passes through the center-hole in the plate d'. The frame-bar is thus radially disposed with respect to the cylinder.

The roll, constructed as thus far described, is not of my invention.

For the purpose of delivering ink to said 50 roll by means embodying this invention, the gudgeon e³ is made tubular or otherwise

formed with a hole e⁵ extended entirely through it longitudinally, to produce an open passage leading to the interior of the hollow cylinder. An end-piece is attached to the hollow gudgeon, herein represented as a collar h, adapted to fit upon the gudgeon, having an attaching-screw h' or other means for securing it thereto. Said end-piece has an internally screw-threaded portion h² at its outer end, preferably made larger in diameter than the hole which receives the gudgeon, to thereby form a seat h³ at the end or bottom of said portion h²; and the gudgeon terminates at said seat. Said end-piece also preferably has a conical flange h⁴, at its outer end surrounding the screw-threaded portion h², said flange having or not having, at its edge, a cylindrical portion h⁵. The screw-threaded portion h² is especially made and provided to receive the screw-threaded nipple of a collapsible tube, which contains the ink to be delivered to the roll, and, as shown in Fig. 3 the nipple i of the collapsible tube is screwed into the end-piece and engages the seat h³ at the end of the screw-threaded portion, and when thus disposed the usual conical end of said tube enters the cylindrical portion h⁵ and engages the conical flange h⁴. The ink will be delivered by compressing the tube in the usual manner, and is forced through the hollow gudgeon into the cylinder. When the collapsible tube is removed, the open end of the screw-threaded portion h² may be closed by an externally screw-threaded plug j.

For convenience in turning the roll and frame-bar, one with relation to the other, manually, a disk k may be secured to the stub shaft b² of the roll, having a serrated edge, and the edge of the cylindrical portion h⁵ may be serrated.

I claim:

1. An ink-roll for printing-presses consisting of a hollow perforated cylinder having journals at its ends and a radially disposed frame-bar therein having gudgeons at its ends arranged co-axially with respect to the cylinder, permitting movement of the frame-bar and cylinder one with respect to the other to force ink through the perforations in the cylinder, one of said gudgeons being made tubular and extended through one of the journals of the cylinder and beyond the end of said journal, a collar arranged on and secured to the end portion of said tubular gudgeon beyond the end of the

journal having an internally screw-threaded portion at its outer end to receive the screw-threaded nipple of a collapsible tube, substantially as described.

- 5 2. An ink-roll for printing-presses consisting of a hollow perforated cylinder, a bar arranged therein adjacent the wall thereof, a pair of radial arms supporting said bar, each arm having at its inner end 10 an outwardly extended gudgeon arranged co-axially with respect to the cylinder permitting movement of the bar and cylinder, one with respect to the other, to force ink through the perforations in the cylinder, one of said gudgeons being made tubular and open at each end, whereby ink may be conducted through it into the cylinder, and means arranged on the tubular gudgeon for connection therewith of a collapsible tube, substantially as described.
- 15 3. An ink-roll for printing-presses consisting of a hollow perforated cylinder and a radially disposed frame-bar therein having gudgeons at its ends permitting movement 20 of the frame-bar and cylinder, one with respect to the other, to force ink through the perforations in the cylinder, one of said gudgeons having a hole through it longitudinally, and an end-piece arranged on the 25 hollow gudgeon having an internally screw-threaded portion adapted to receive the screw-threaded nipple of a collapsible tube, said screw-threaded portion being made of 30 larger diameter than the gudgeon and having a seat at the bottom, substantially as described.
- 35 4. An ink-roll for printing-presses consisting of a hollow perforated cylinder and a radially disposed frame-bar therein having 40 gudgeons at its ends permitting movement of the bar and cylinder, one with respect to the other, to force ink through the perforations in the cylinder, one of said gudgeons

having a hole through it longitudinally, and an end-piece arranged on the hollow gudgeon having an internally screw-threaded portion to receive the screw-threaded nipple of a collapsible tube and having means surrounding said screw-threaded portion to support the end of the tube, substantially as described.

5. An ink-roll for printing presses, consisting of a hollow perforated cylinder and a radially disposed frame-bar therein having gudgeons at its ends permitting movement 55 of the frame-bar and cylinder, one with respect to the other, to force ink through the perforations in the cylinder, one of said gudgeons having a hole through it longitudinally, and an end-piece arranged on the 60 hollow gudgeon having an internally screw-threaded portion to receive the screw-threaded nipple of a collapsible tube, and having a conical flange surrounding said screw-threaded portion adapted to be engaged by 65 the end of said tube, substantially as described.

6. An ink-roll for printing presses, consisting of a hollow perforated cylinder and a radially disposed frame-bar therein having 70 gudgeons at its ends permitting movement of the frame-bar and cylinder, one with respect to the other, to force ink through the perforations in the cylinder, means connected 75 with the cylinder and means connected with the frame-bar, arranged to be manually engaged, to turn one with relation to the other, substantially as described.

In testimony whereof, I have signed my name to this specification, in the presence 80 of two subscribing witnesses.

HARMON P. ELLIOTT.
